UNITED STATES PATENT OFFICE.

MAX TOLTZ, OF ST. PAUL, MINNESOTA, ASSIGNOR, BY MESNE ASSIGNMENTS, TO LOCOMOTIVE SUPERHEATER COMPANY, OF WILMINGTON, DELAWARE, A CORPORATION OF DELAWARE.

STEAM-SUPERHEATER.

1,093,954.

Specification of Letters Patent. Patented Apr. 21, 1914.

Application filed November 4, 1910. Serial No. 590,699.

To all whom it may concern:

Be it known that I, MAX TOLTZ, a citizen of the United States, residing at St. Paul, Ramsey county, Minnesota, have invented 5 certain new and useful Improvements in Steam-Superheaters, of which the following is a full, clear, and exact description, such as will enable others skilled in the art to make and use the same.

10 My invention relates to improvements in steam superheaters and has special reference to improved means for connecting superheater elements, tubes, or loops with the saturate and superheated steam headers, 15 which therewith, comprise the superheater.

The object of my invention is to provide an improved superheater, in which each element, tube or loop, so-called, of the superheater shall be separately connected with 20 the superheater headers in such manner that they may be quickly disconnected from the same and as easily reconnected. Other objects of the invention will appear hereinafter.

25 My invention consists generally in superheater headers having openings or ducts in their sides, in combination with a block or connector, suitably secured to the headers and containing angle or elbow passages which 30 communicate with respective openings or ducts thereof, and a superheater element, tube or loop, the ends of which are attached to said block and communicate with respective elbow passages therein.

35 The invention also consists in various details of construction and in combinations of parts, all as hereinafter described and particularly pointed out in the claims.

My invention will be more readily understood 40 by reference to the accompanying drawing, forming part of this specification and in which:—

Figure 1 is a vertical sectional view, 45 illustrating a saturate steam header, a superheated steam header, and two superheater elements or loops connected therewith, in accordance with my invention; Fig. 2 is a plan view, and Fig. 3 is a detailed vertical section on the line X X of Fig. 2.

50 As shown in the drawings, 2 represents the front flue sheet of a locomotive or like flue boiler, and 3, 3 are enlarged fire-flues, having their ends secured in the flue sheet 2. 4, 4 are superheater elements, pipes or

loops, of the double return type. These are 5 arranged in the tubes 3, 3.

The ends of the superheater loops are connected with the saturate and superheated steam headers A and B, which latter are connected respectively to the dry pipe of the 6 boiler and to the steam chest or chests of the engines. The superheater elements 4, 4 conduct the steam from the saturate steam header A to the superheated steam header B, and the loops or elements being subject- 6 to the heat of the fire box gases in the flues 3 the steam flowing in said elements is raised to a high temperature before being delivered to the steam chests of the engines.

My invention is particularly concerned 7 with the improvement of the means of connecting the superheater elements with the headers, and I shall hereinafter describe these connections in detail. But first I desire that it shall be understood that the fire 7 tube 3 in Fig. 2 is representative of a row of fire tubes extending across the boiler or vertically therein, parallel with, and according to the position of, the steam headers A and B; which latter may be arranged 8 either horizontally or vertically in the smoke box of the boiler. In like manner the tubes, 3—3, of Fig. 1 represent not one row but two parallel rows of fire tubes, which obviously are parallel to the headers. I 8 prefer that the headers shall be arranged edge to edge, that is, one in front of the other, and that they shall occupy a position relatively between the two rows of enlarged fire flues in the boiler. The superheater elements are of identical construction throughout but occupy reverse positions in the parallel rows of flues. The ends of the superheater pipes or elements extend out of the fire tubes 3 and lie parallel with the sides of 9 the headers, projecting part way across the side.

The headers A and B are preferably of the same thickness, so that their sides A' B' are in the same planes. I prefer that the 1 headers shall be substantially separate, as indicated by the slots, a, in Fig. 2, but preferably form them in a single casting, the adjacent edges being connected by the integral webs b. The webs b, between the headers A and B are arranged at the same intervals as the pairs of fire tubes 3, 3, and each web is provided with a square hole c, as in-

2
dicated by dotted lines in Fig. 2. These square holes extend from side to side of the headers and are adapted to contain the bolts 5, by means of which the hereinafter described connectors, belonging to the pairs of superheater elements, are fastened or secured upon the sides of the headers. The sides of the headers are provided with steam outlet and inlet openings or ducts A'' 10 and B'' respectively, these being arranged near the inner walls of the headers as shown.

From the foregoing it will be understood that a plurality or large number of pairs of superheater elements are connected with a single pair of headers, A and B. In speaking of the headers I shall refer to the upper and lower sides thereof, but it will be understood that these terms are relative and change their meaning according to the position of the headers in the smoke box. The terms "pair of flues" and "pair of elements" as hereinafter used, are intended to define two flues or two elements, one above the other, on opposite sides of the headers 25 A and B.

The connectors are of identical construction, and therefore the description of the connectors belonging to the elements of a single pair, together with the method of attaching the same to the headers, will serve to describe the several pairs of elements and connectors which go to make up a complete superheater. The ends or terminals 4' and 4'' of the superheater elements are preferably, but not necessarily, slightly bent or separated, as shown in Fig. 2, but the extreme ends of the pipes are parallel, in order that they may be conveniently telescoped into the openings provided therefor in the connectors or blocks 6, 6. One such connector 6 is provided for each superheater element and each serves to mechanically connect the ends of its element. The block or connector does not, however, place the ends of the element in communication but instead is provided with two independent elbow passages 7 each located in an ear 9, to which the ends 4' and 4'' of the element are joined and thereby placed in communication with corresponding openings A'' and B'' of the headers A and B. The openings A'' and B'' in the headers are arranged in line with the ends 4' and 4'' of corresponding elements and hence are relatively staggered in the headers. If desired the connector or block may be substantially rectangular in form, but as the elbow passages therein must connect with the holes in the headers I prefer that the connector shall occupy a relatively diagonal position upon the headers, and therefore elongate the block diagonally and, so to speak, cut away the unnecessary metal which would be used in making the block rectangular. The only advantage in making the block rec-

tangular would be to make the ends of the superheater element of the same length, and I do not do this as I find that the ends of the element may conveniently be of different lengths as shown in Figs. 1 and 2. Interfitting bosses and seats 7' are provided at the ends of the connector and at the openings A'' B'', and the surfaces of these are either ground or suitable packing is interposed to make tight joints. The elbow passage at each end of the connector comprises a part 7'' which connects with the opening or duct in the side of the header and another portion 7''' at right angles thereto, the latter receiving the end 4' or 4'' of the superheater element, as best shown in Fig. 3. It is necessary to bore out the passage 7''' to make a snug fit with the end of the superheater pipe, and in doing this the hole is bored clear through the end of the connector, the outer end of the hole being then threaded to receive the plug 8. The end of the superheater pipe is expanded in the opening 7''' before the plug 8 is screwed into place. It will be obvious that the plug may be removed at any time when it is necessary to close or repair the end of the element, and then replaced. The particular advantage of the connector herein shown is that the plugs 8, 8 thereof are presented on the outer side of the superheater, in which positions they are readily accessible from the front of the smoke box. The inner side or end 9 of the block or connector is preferably faced off perpendicularly to the ends of the superheater pipes, but the irregular intermediate surface between these surfaces need not be finished. The middle of each connector contains a hole for the bolt 5. The connectors are directly opposite one another on the sides of the headers though preferably reversed in position, and the bolt 5 extends through both connectors or blocks. The ends of the bolt are threaded and the connectors are tightened on the headers by means of nuts 5', and the bolt may be taken out and both connectors freed from the headers on removal of either of the nuts 5'. Separate bolts or cap screws may be used with the connectors or blocks, but the single bolt is best, particularly in cases where several pairs of superheater headers are used in the same superheater, in which case the pairs of headers occupy parallel positions and the bolts must be removed from the outer sides thereof.

As various modifications of my invention will readily suggest themselves to one skilled in the art, I do not confine the invention to the specific constructions herein shown and described.

Having thus described my invention, I claim as new and desire to secure by Letters Patent:

1. In a steam superheater, a pair of head-

- ers arranged one in front of the other across the smoke box and with their sides in substantially the same plane, a superheater element or loop having a short and a long end, 5 an elongated integral connector having a pair of independent wholly separated elbow passages one at each end, one pair of corresponding ends of the two passages going to different headers and the other pair of ends 10 having the aforesaid long and short element ends joined respectively thereto, and means for fastening the connector to the headers.
2. In a steam superheater, a saturated and a superheated steam header arranged edge on 15 one in front of the other across the smoke box with their side faces substantially in the same planes and perpendicular to the flue sheets, each header having a hole on a corresponding side face, a superheater element, a 20 connector block clamped against the headers and provided with independent elbow passages at opposite ends communicating respectively with the aforesaid header holes said elbow passages being, at their ends remote 25 from the header holes, parallel with the aforesaid side faces and receiving the ends of the superheater element.
3. In a steam superheater, a saturated and a superheated steam header arranged edge 0 on one in front of the other across the smoke box with their side faces substantially in the same planes and perpendicular to the flue sheets, each header having a pair of holes one on each side face, a superheater element, a pair of connector blocks on opposite side faces of the two headers each provided with independent elbow passages at opposite ends communicating respectively with the aforesaid header holes on one side face of the two headers said elbow passages being, at their ends remote from the header holes, parallel with the aforesaid side faces and receiving the ends of the superheater element,
- and means for securing the connector blocks in place. 45
4. In a steam superheater, a superheater element or loop adapted to be placed in the flue of a boiler, in combination with a connector or block joining the ends of said loop and provided with cavities, coaxial with, and 50 to receive respective ends thereof, plugs closing the outer ends of said cavities and said cavities having substantially right angled ducts for connection to saturate and superheated steam headers respectively, substantially as described. 55
5. In a steam superheater, a pair of headers arranged edge to edge and provided with holes in their sides, in combination with a bolt extending through said headers, a pair 60 of connectors or blocks, secured upon opposite sides of the headers by said bolt and containing elbow passages communicating with respective holes in the headers, and a pair of superheater elements, the ends of which 65 extend into the elbow passages of respective blocks, substantially as described.
6. A boiler and its enlarged fire flues, in combination with a pair of superheater elements arranged in said fire flues, an integral 70 connector block joining the ends of each loop and containing independent completely separated elbow passages communicating therewith, and a pair of headers arranged between said blocks, communicating with respective passages thereof and whereto said blocks are detachably secured, substantially 75 as described.
- In testimony whereof, I have hereunto set my hand this 31st day of October, 1910, in the presence of two subscribing witnesses.

MAX TOLTZ.
